UNITED STATES PATENT OFFICE.

DAVID D. GORDON, OF CHICAGO, ILLINOIS, ASSIGNOR TO ECONOMY FUSE AND MANUFACTURING COMPANY, OF CHICAGO, ILLINOIS, A CORPORATION OF NEW YORK.

PULL SWITCH.

Application filed February 15, 1926 Serial No. 88,174.

The present invention relates to improvements in pull switches.

More particularly the present invention relates to electric switches of the pull socket type, wherein it is desirable that successive pulls in the same general direction upon a chain or other operating member will result in the successive making and breaking of an electric circuit.

10 An object of the present invention is to provide a pull socket which is simple and cheap to construct.

A further object is to provide a pull socket which is sturdy and reliable in service.

15 A further object is to provide an improved pull socket in which switching is accomplished with a snap action.

Further objects will appear as the description proceeds.

20 Referring to the drawings—

Figure 1 is a view in side elevation of a pull socket;

25 Figure 2 is a longitudinal sectional view of the structure shown in Figure 1, Figure 2 being on a larger scale than is Figure 1;

Figure 3 is a transverse sectional view taken along the plane indicated by the arrows 3—3 of Figure 2, the switch parts being shown in one biased position;

30 Figure 4 is a view similar to Figure 3, but showing the switch parts in their alternative biased position; and

Figure 5 is a view showing a portion of the structure illustrated in Figure 3, the parts 35 being shown independently of the other structure in Figure 3 for purposes of clarity.

The numeral 10 indicates a casing or shell which may be provided with the cap 11. The bell mouth 12 provides a guide for the pull member 13, which is indicated in the form of a chain. It will be clear, of course, that the operating member 13 may take any other preferred form.

40 The shell 10 is provided on its interior with the insulating sleeve 14, which houses the screw-threaded conducting sleeve 15. Mounted centrally of the conducting sleeve 15, but insulated therefrom, is the usual center contact 16. The numeral 17 indicates a conducting member which may have the double function of holding the sleeve 15 in place and forming an electrical connection between said sleeve 15 and one of the two wires of an electric circuit. The connection between said 45 member 17 and a binding screw such as is

ordinarily provided in electric light sockets is not shown, inasmuch as such a showing is not necessary for a complete understanding of the invention. The other side of the electric circuit referred to is connected to the conducting pin 18, which is carried by a member 19 of insulating material. Cooperating with the pin 18 and in alignment therewith is the conducting pin 20, which is connected to the center contact 16 and electrically insulated from the sleeve 15. The member 21 disposed above the sleeve 15 and suitably supported from the insulating member 19 may form a support for said contact pin 20. Said member 21 also forms a support for certain switching mechanism indicated as a whole by the numeral 22, which switching mechanism cooperates with the aligned pins 18 and 20. It will be clear that when the aligned pins 18 and 20 are bridged by an electric conductor, 60 the circuit of the electric socket will be complete, assuming of course that a translating device or other means is in use to connect the sleeve 15 and center contact 16.

65 For the purpose of providing a bridge between the aligned contact pins 18 and 20, a U-shaped bridging member 23 is provided, which bridging member is pivotally mounted between the legs of a U-shaped support 24 forming part of the switching mechanism 22. 70 Said U-shaped contact member 23 is adapted to have a swinging movement about the axis 25, the limits of said movement being defined by the aligned contact pins 18 and 20 on the one side and by the stop 26 on the other side. 75

80 For the purpose of selectively positioning the contact member 23, certain control mechanism is provided, which will now be described. Carried by the supporting member 24 for swinging movement about the axis 25 is the U-shaped member 27 having the two pins 28 and 29 projecting from the upper extremity thereof. The pin 28 provides a pivot pin for the yoke member or operating member 30, which yoke member has the two legs 31—31, which legs 31—31 are adapted to receive between them the pin 29. The outer extremity of the yoke 30 forms a connection for the pull member 13. Stops 32—32 are provided which define the limits of the swinging movement of the U-shaped member 27. Stops 33—33 are also provided, which define the limits of the swinging movement of the yoke 30. 85

90 A tension spring 34 is provided for attach- 95

110

ment to the outer extremities of the U-shaped members 23 and 27, said spring normally tending to draw together the base portions of said U-shaped members 23 and 27. It will be clear that said spring 34 will selectively bias the U-shaped member 23 either toward the contact member 20 or the stop 26, depending upon the position of said spring 34 relative to the axis 25 about which said 10 U-shaped member 23 swings. The showing of the spring 34 has been omitted from Figures 3 and 4 in order that the drawing may not be complicated by a multiplicity of lines. The line of action of said spring is indicated, 15 however, in said figures by the broken line 34^a. The mode of operation of the above described embodiment of the present invention is as follows. Starting with the parts as indicated in Figure 3, it will be clear that the 20 spring 34, acting along the line indicated by the numeral 34^a, will hold the U-shaped members 23 and 27 against the pin 20 and lower stop 32, respectively. By reason of the fact that the contact pin 20 is in alignment 25 with the contact pin 28, a bridging relationship is established at this time between said contact pins 20 and 18. At this time the yoke 30 is disposed with the upper leg 31 thereof in engagement with the pin 29, which 30 pin, as noted above, is carried by the U-shaped member 27. In this position the pull member 13 is disposed upwardly, as the parts are viewed in Figure 3, of the pivotal axis 28 of the yoke 30. A pull upon the pull member 13 will therefore tend to swing the yoke 30 in a counterclockwise direction about the pivotal axis 28. This action will tend to raise the U-shaped member 27, as the parts are viewed in Figure 3, until the line of action 35 34^a of the spring 34 is above the axis 25, at which time said U-shaped members 23 and 27 will be snapped by the spring 34 into engagement with the stop 26 and upper stop 32, respectively, thereby breaking the bridging 40 relationship between the contact pins 18 and 20. The upper stop 32 will limit the counterclockwise movement of the yoke member 30, and when the U-shaped member 27 has been moved, as above described, into engagement 45 with the upper stop 32, the relative positions of the yoke member 30 and U-shaped member 27 will be changed to that shown in Figure 50 4, wherein the lower leg 31 of said yoke 30 is in engagement with the pin 29. At this time the line of action of the pull member 13 will be below the axis 25 as the parts are viewed in Figures 3 and 4. The next pull 55 upon the member 13 will therefore tend to move the U-shaped member 27 in a clockwise direction against the lower stop 32, resulting 60 in the movement of the parts back to the positions shown in Figure 3.

The above described cycle of operation is 65 performed with a minimum of parts which may be cheaply constructed and cheaply as-

sembled and which will stand up well in service.

Though a preferred embodiment of the present invention has been described in detail, many modifications will occur to those skilled in the art. It is intended to cover all such modifications that fall within the scope of the appended claims.

I claim:

1. A pull switch comprising, in combination, a supporting member, a pair of swinging members supported thereby, a spring biasing the outer extremities of said swinging members toward each other, one of said swinging members comprising an electrical conductor, stops for limiting the swinging movement of said swinging members, one of said swinging members having an operating member pivotally supported thereby, said operating member having spaced portions adapted to abut against its corresponding swinging member to change the relative positions of said swinging members.

2. A pull switch comprising, in combination, a supporting member, a pair of swinging members supported thereby, a spring biasing the outer extremities of said swinging members toward each other, one of said swinging members comprising an electrical conductor, stops for limiting the swinging movement of said swinging members, one of said swinging members having an operating member pivotally supported thereby, said operating member having spaced portions adapted to abut against its corresponding swinging member to change the relative positions of said swinging members, and stop means for said operating member for changing the position of said operating member relative to its corresponding swinging member.

3. In a pull switch, in combination, supporting means, a pair of swinging members having a common axis supported by said supporting member, spring means for biasing the outer extremities of said swinging members toward each other, stops for limiting the swinging movement of each of said swinging members, one of said swinging members having an operating member pivoted thereto near the outer extremity thereof, said operating member having spaced operating portions adapted to abut against a portion of the corresponding swinging member to move said swinging member in opposition to said spring means, and stop members for engaging said operating member to change the position of said operating member relative to its corresponding swinging member.

4. In a pull switch, in combination, supporting means, a pair of swinging members having a common axis supported by said supporting member, spring means for biasing the outer extremities of said swinging members toward each other, stops for limiting the

swinging movement of each of said swinging members, one of said swinging members having an operating member pivoted thereto near the outer extremity thereof, said operating member having spaced operating portions adapted to abut against a portion of the corresponding swinging member to move said swinging member in opposition to said spring means.

10 5. In a pull switch, in combination, a supporting member, a pair of swinging members supported thereby about a common axis, stops for limiting the movement of said swinging members, a spring for biasing said 15 swinging members selectively against one set of stops or against the other set of stops, an

operating member swingingly carried by one of said swinging members, said operating member having spaced operating portions adapted to abut against a portion of the corresponding swinging member to move said swinging member in opposition to said spring, a pull member for controlling said operating member, and stops adapted to be engaged by said operating member for changing the position of said operating member whereby to move the line of operation of said push member from one side to the other of said axis.

Signed at Chicago, Illinois, this 10th day 30
of February, 1926.

DAVID D. GORDON.
